UNITED STATES PATENT OFFICE.

JOEL SASIENI, OF STOKE NEWINGTON, LONDON, ENGLAND.

TOBACCO PIPE.

Application filed July 7, 1924. Serial No. 724,690.

To all whom it may concern:

Be it known that I, JOEL SASIENI, a British subject, residing at Stoke Newington, London, England, have invented certain new and useful Improvements in and Relating to Tobacco Pipes, of which the following is a specification.

This invention relates to tobacco pipes, cigar holders and the like of the kind in which the smoke is caused to pass through an annular chamber (formed around an extension from the mouthpiece that passes through an enlarged cylindrical cavity in the stem) on its way to the mouthpiece and has for its object improvements whereby moisture is prevented from passing between the mouthpiece and bowl of a pipe or holder and the socket part of the mouthpiece is strengthened.

20 Pipes as well as cigar and cigarette holders of the kind referred to, have been provided with a straight upwardly inclined bore extending between the mouthpiece and the upper part of the annular chamber at 25 one end and between the bowl or holder and the upper part of the said annular chamber at the other end where the extension from the mouthpiece was provided with an enlarged part that was adapted to make an airtight joint between the said straight upwardly inclined bore at that end and the usual bore in the stem leading to the said bowl or holder. The object of this construction is to cause moisture entering or deposited 30 in the annular chamber to fall to the bottom of it and so leave a sufficient space above for the dry smoke to pass freely from the bowl or holder to the mouthpiece.

With pipes of this construction it is found 40 that when the moisture that frequently accumulates in the bore of the mouthpiece is blown into the chamber formed between the said extension and the bore of the pipe stem it is caused to assume a more or less distorted globular form by reason of its surface tension and the fact that the said chamber is covered with the greasy oil of the tobacco.

If the smoker discharges this globule of moisture by blowing through the mouthpiece vigorously, it is shot to the opposite end of the chamber and through the bore in the enlarged end of the extension and thence into the pipe bowl or holder before gravity has time to cause the moisture to fall to the 55 lower part of said chamber so as to be trapped therein.

I have found that by providing the extension between the inner end of the mouthpiece and the enlarged end of said extension with a reduced part the surface tension of the moisture is afforded an opportunity of pulling the elongated drop of moisture into a form that more closely approximates the spherical and that the said drop on reaching the further end of the reduced part meets with a resistance to its forward movement that causes it to fall to the bottom of the chamber.

The present invention further consists in providing the aforesaid extension with a long tubular coupling part adapted to extend through the socket or push which is of reduced diameter into the mouthpiece so as to strengthen the push and so prevent its being broken off when the smoker knocks the ash out of his pipe.

I will now proceed to more particularly describe my invention with the aid of the accompanying drawing which shows a longitudinal section through a pipe embodying the present improvements.

According to the construction shown, the extension *i* has an enlarged end *j* adapted to abut against the end of the chamber *k* so as to form an airtight joint at that point and is provided with a tubular part *f* that extends through the push *d* into the mouthpiece *c*. The shoulder *h* is provided with a straight bore *l* which extends from the upper side of the said shoulder *h* to the screw-threaded end of the tubular part *f* where it joins the bore of the mouthpiece. The enlarged end *j* of the extension *i* is also provided with a straight bore *m* extending from its upper side to the reduced inner end *n* of the bore leading to the pipe bowl *a*.

In order to prevent the moisture that accumulates in the bore of the mouthpiece from being blown across the upper part of the chamber *k* in the form of an elongated drop to the bore *m* in the enlarged end *j* and thence through the inner end *n* of the bore in the pipe stem into the bowl *a*, I provide the extension *i* with a reduced portion or neck *o* within which the surface tension of the moisture causes the drop to assume a more spherical form whose forward progress is hindered by the narrower space beyond the neck which causes said drop to fall to the lower part of the chamber *k*.

By making the upwardly inclined bores straight cleaning is facilitated and in order

that the mouth-piece may be inserted with the bores directed upwardly it is provided with a suitable mark.

I claim:

5 A tobacco pipe, consisting of a part having a stem formed with a long cylindrical cavity, in combination with a mouthpiece consisting of a body and an extension passing through said cavity and having its exterior faces fully exposed to the walls of said cavity and formed with an enlarged free end portion, an enlarged portion adjacent to said body, short portions of smaller cross-sectional size extending toward each 10 other from the opposed faces of said enlarged portions, and a medial neck of 15 greatly reduced diameter connecting said

short portions, the ends of which constitute abrupt end shoulders for said neck, the said body, extension and enlarged portions of the latter being formed with bores forming communication through the upper part of said cavity with the atmosphere, whereby any globules of tobacco oil and moisture on said extension will move thereon to the neck thereof and drop therefrom to the bottom of the cavity and the smoke will be drawn into the upper part of said cavity and from the upper part of said cavity.

In testimony whereof, I have signed my name to this specification at 61 and 62, Chancery Lane, London, England, this 27th day of June, 1924.

JOEL SASIENI.
